UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

DUPLICATING APPARATUS.

No. 823,937.

Specification of Letters Patent.

Patented June 19, 1906.

Application filed January 15, 1906. Serial No. 296,177.

To all whom it may concern:

Be it known that I, ALBERT B. DICK, a citizen of the United States, residing at Lake Forest, in the county of Lake and State of Illinois, have invented a certain new and useful Improvement in Duplicating Apparatus, of which the following is a specification.

The invention relates generally to duplicating apparatus, and is adapted particularly for use with that type of such apparatus in which are employed a rotary drum carrying upon its periphery a stencil-sheet and an underlying pressure-roller, between which and the periphery of such drum impression-sheets are successively passed in order to imprint thereupon the characters cut in the stencil-sheet.

The object of the invention is to desirably simplify apparatus of this character with respect particularly to the paper-stopping device by means whereof the proper position of the impression-sheet prior to the coaction therewith of the stencil is determined.

In carrying out the invention in a preferred form the pressure-roller, which underlies the stencil-carrying drum, is mounted upon hinged arms operated both by a suitable "throw-off" mechanism and by a connection with the drum, the former being used to throw the pressure-roller to inoperative position when the machine is out of use and the latter permitting the pressure-roller to coact with the drum only at that point of such drum which is covered by the stencil. Carried also by these hinged arms is a paper-stopping mechanism comprising a bar extending in a plane parallel with the axis of the pressure-roller and in close proximity to the periphery of such roller when in operative position. This bar, or an appurtenance thereof, has a connection with a fixed part of the apparatus, and due to this connection its movement is interdependent with that of the pressure-roller, one of these being in operative position only when the other is in inoperative position.

The invention is illustrated in the accompanying drawings, in which—

Figure 1 is a central longitudinal section of a duplicating apparatus employing my invention. Fig. 2 is a transverse section on the line 2 2, Fig. 1. Fig. 3 is a section on the line 3 3, Fig. 2, looking in the direction of the arrows adjacent to that line and illustrating the

paper-stop in operative position; and Fig. 4 is a section of certain parts as shown in Fig. 1, but illustrating the paper-stop in inoperative position.

Referring to the drawings, A designates a suitable base upon which are mounted the side members B B of the frame. C designates the stencil-carrying drum pivotally mounted in said side members by means of suitable stub-shafts c c. Movement is transmitted to said drum by means of crank c' and pinions c² c³. One of the stub-shafts c carries a cam c⁴, coacting with a sheave c⁵, carried by a vertically-oscillating bar c⁶, the upper end whereof is guided by having a slot cut therein, through which the shaft c extends.

D designates a rock-shaft, the ends whereof are journaled in the side members B B of the frame. Adjustably mounted upon this shaft is a collar d, secured to or formed integral with which are two arms d' d', the end of the arm d' being pivotally secured at d³ to the vertically-oscillating bar c⁶. At the opposite side the rock-shaft D is provided with a collar E, also adjustably secured upon said rock-shaft, and secured to or formed integral with this is an arm e, similar to the arm d'. Each of said arms d' and e is provided with a lug e', to the free end of which is secured one end of a coil-spring e², the other end of said coil-spring being secured, as at e³, to the frame of the machine. The office of the coil-spring e² is to yieldingly position the pressure-roller, presently described, by holding the sheave c⁵, carried by the vertically-oscillating bar c⁶, in contact with the cam c⁴.

F designates the pressure-roller, the shaft f whereof is journaled in the arms e d'. G designates the paper-stop, here shown as comprising a bar supported adjacent to each end by means of brackets g, the ends whereof are pivoted at g' g' to the arms e d'. g³ designates a link pivoted at its upper end to an ear formed upon one of the brackets g and at its lower end to a stud g', secured to one of the side members of the frame. If desired, I may employ a spring g² for keeping the parts just described under tension and to prevent the rattling thereof. As will be seen, (see particularly Fig. 3,) the movement of the paper-stop G is dependent upon that of the pressure-roller F, with which said stop coacts in order to determine the degree of forward

movement of the impression-sheet in advance of the printing operation. Said stop is shown in the figure last mentioned, as well as in Figs. 1 and 2, in operative position. Here it opposes the further movement of the impression-sheet *h*. The pressure-roller *F* is in inoperative position, being moved thereto by the engagement of the cam *c⁴* with the sheave *c⁵*, carried by the vertically-oscillating bar *c⁶*.

10 The continued movement of the drum, and therefore of the cam *c⁴*, permits the pressure-roller to rise to operative position, in which it is shown in Fig. 4, the same thereby gripping the impression-sheet which is passed from the machine by the coaction of the pressure-roller and the drum and simultaneously imprinted upon. As the pressure-roller *F* and therefore the arms *e* *d²* rise to this operative position the paper-stop *G* and its brackets *g g* are

15 rocked upon the pivotal point *g'* by reason of the link *g³*, and thereby thrown to inoperative position, Fig. 4, out of the way of the advancing edge of the impression-sheet.

It will be seen that the mechanism thus described is very simple both in construction and operation, requiring but few parts; but these are positively and reliably actuated to meet the requirements of practical use.

Having now described my invention, what

20 I claim as new therein, and desire to secure by Letters Patent, is as follows:

1. In duplicating apparatus, the combination with a drum and an underlying pressure-roller pivotally mounted in movable arms, of a paper-stop supported on said arms and movable relatively thereto, substantially as set forth.

2. In duplicating apparatus, the combination with a drum and an underlying pressure-roller pivotally mounted in movable arms, of a paper-stop pivoted to said arms and movable to operative and inoperative positions, substantially as set forth.

3. In duplicating apparatus, the combination with a drum and an underlying pressure-roller mounted upon hinged arms, of a paper-stop movably carried by said arms, and a connection between said paper-stop and a fixed part of the apparatus, substantially as set forth.

4. In duplicating apparatus, the combination with a drum and an underlying pressure-roller mounted upon hinged arms, of a paper-stop pivotally mounted upon said arms, and a link pivotally connected at one end to said paper-stop and pivotally connected at the other end to a fixed part of the apparatus, substantially as set forth.

5. In duplicating apparatus, the combination with a drum, of a rock-shaft, arms carried by said rock-shaft, a pressure-roller journaled in said arms, a paper-stop comprising a bar arranged in a plane parallel with the axis of said roller and supported by brackets pivotally connected with said arms, and a link movably connected with one of said brackets and with a fixed part of the apparatus, substantially as set forth.

6. In duplicating apparatus, the combination with a drum, of a rock-shaft, arms carried by said rock-shaft, a pressure-roller journaled in said arms, a paper-stop comprising a bar arranged in a plane parallel with the axis of said roller and supported adjacent to its ends by brackets pivotally connected with said arms, and a link pivotally connected at one end to one of said brackets at a point displaced from the longitudinal axis of the bracket and at its other end to a fixed part of the apparatus, substantially as set forth.

This specification signed and witnessed this 11th day of January, 1906.

ALBERT B. DICK.
